[57] CLAIM

The ornamental design for a field hockey stick, sub-
stantially as shown and described.

DESCRIPTION

FIG. 1 is a perspective view of a field hockey stick,
showing our new design.

FIG. 2 is an enlarged fragmentary view of the blade
portion,

FIG. 3 is a bottom view thereof,

FIG. 4 is a right side elevational view thereof,

FIG. 5 is a top plan view thereof,

FIG. 6 is a view of the opposite side of FIG. 2, and

FIG. 7 is an elevational view taken from the right of
FIG. 6.

FIG. 1

FIG. 2

FIG. 4

FIG. 3

FIG. 5

FIG. 6

FIG. 7
